UNITED STATES PATENT OFFICE.

LEON ALEXANDER DE BECKER, OF ST. MARGARETS-ON-THAMES, ENGLAND.

CARBURETOR FOR INTERNAL-COMBUSTION ENGINES.

Application filed September 2, 1921. Serial No. 498,031.

To all whom it may concern:

Be it known that I, LEON ALEXANDER DE BECKER, a subject of the King of Great Britain and Ireland, residing at The Limes, 5 The Avenue, St. Margarets-on-Thames, in the county of Middlesex, England, have invented new and useful Improvements in Carburetors for Internal-Combustion Engines (for which I filed application in Great 10 Britain No. 5450, Feb. 23, 1920), of which the following is a specification.

The invention relates to carburetors for internal combustion engines and has been devised with the object of producing a carburetor which will enable an internal combustion engine run on paraffin to be started with the same fuel. The invention will also be found to be useful in the case of engines run on some of the indifferent qualities of liquid fuel sold at the present time as petrol or in the case of any liquid fuel or mixture of liquid fuels which can not be readily vaporized at the start.

The invention consists of a pre-heater and 25 vaporizer to be applied to the jet of a carburetor, which can be used with many types of carburetors without entailing any structural alterations in the parts of said carburetors.

30 Said pre-heater and vaporizer consists essentially of an aggregation or mass of somewhat porous carbon or, if desired, graphite, which is mounted on the jet of a carburetor in such manner as to be insulated therefrom and is electrically connected to a battery. The pre-heater and vaporizer so long as it is made of a size corresponding to the jet to which it is to be applied and is electrically insulated 35 therefrom may be constructed or built up in any suitable way. For instance it may, and preferably does, consist of a sleeve of carbon of uniform diameter throughout its length which is insulated from the jet of the carburetor by means of mica or other insulating material. The sides of said sleeve of carbon may be fluted or be provided with spirally disposed ribs. Alternatively the pre-heater and vaporizer may 40 be constructed of a number of segments of carbon separated from one another by fins formed on a flanged tube of porcelain or other non-conducting material, or of a number of discs of carbon, which may vary in diameter, separated from one another by 45 discs of non-conducting material and sup-

ported on a flanged tube of porcelain or other non-conducting material, or of a number of concentric sleeves of carbon supported on a flanged tube of porcelain or other non-conducting material. In all of the three alternative constructions of the pre-heater and vaporizer above referred to the separate carbon parts, namely the segments, discs and sleeves, are electrically 50 connected to one another so that all of them will be heated by the passage of an electric current.

The invention is illustrated by the accompanying drawings.

Fig. 1 is a vertical section, drawn to an enlarged scale, of the preferred construction of the pre-heater and vaporizer, illustrating a way in which the latter may be connected to the leads running to a battery. 70 Fig. 2 is a plan, drawn to the same scale, of the same construction of pre-heater and vaporizer, certain parts shown in Fig. 1 being omitted. Fig. 3 is a plan, drawn to a reduced scale, of one of the L-shaped strips 80 of metal which serve as a means for enabling the pre-heater and vaporizer to be connected to said leads. Figs. 4 and 5 are perspective fractional views illustrating two stages in the bending of said metal 85 strips. Fig. 6 is a vertical section and Fig. 7 is a plan of an alternative construction of the pre-heater and vaporizer in which the carbon parts thereof consist of segments. Figs. 8 and 9, and Figs. 10 and 11, are 90 views, corresponding to Figs. 6 and 7, illustrating further constructions of the pre-heater and vaporizer, in which the carbon parts thereof consist respectively of discs and concentric sleeves. Fig. 12 is a vertical 95 section illustrating a carburetor provided with the preferred construction of pre-heater and vaporizer.

Referring first to the construction of pre-heater and vaporizer illustrated by Figs. 100 1 and 2, and shown in Fig. 12, 1 is a sleeve which is preferably made of carbon, somewhat porous carbon, though it may consist of graphite. 2 is mica by which the sleeve 1 is insulated from the jet of the carburetor 105 to which the sleeve is to be applied. 3 are metal rings in close contact with upper and lower parts of the sleeve 1. These rings form parts of strips 3¹ of metal, which are made, as shown in Fig. 3, of substantially 110 L-shape, that is to say are provided with two limbs 3¹¹ and 3¹¹¹ disposed at right angles

to one another, namely a shorter limb 3^{II}, which is made of definite length, and a longer limb 3^{III} which is provided at its outer end with a pair of slots 3^{IV} for enabling the 5 leads running to the battery to be connected to the strips 3^I. The strips 3^I are secured in position on the pre-heater and vaporizer in the manner now to be described. The shorter limb 3^{II} of each strip is bent at its end 10 so as to provide a hook 3^V the outer part of which is located at a distance from the contiguous parts of the strip corresponding to the thickness of the strip. The remainder of the shorter limb 3^{II} of each strip 15 is bent to such shape as to fit the exterior of the pre-heater and vaporizer, and the longer limb 3^{III} of the strip is bent upwards at right angles to the shorter limb, a space corresponding to the thickness of the strip 20 being left between the contiguous parts of this portion of the strip. The bent strip will then be of the shape shown in Fig. 4. The hooked part 3^V of the shorter limb 3^{II} of the strip is now engaged with the junction 25 of the two limbs of the strip, that is to say the inner portion of the hooked part 3^V of the strip is passed into the space obtaining between the contiguous parts of the two limbs of the strip. The longer limb 3^{III} of the strip is now bent downwards, that is to say in the opposite direction to that in which it has previously been bent, so as to secure 30 in position the interengaging parts of the strip. The appearance of the strip will now 35 be that illustrated by Fig. 5. After the strips 3^I have been secured in position on the pre-heater and vaporizer the strips are connected to wires 4 leading to the battery by passing them through the slots 3^{IV} formed 40 in the outer parts of the longer limbs 3^{III} of the strips. Asbestos 5 is then placed between the outer parts of the longer limbs 3^{III} of the strips 3^I, and said limbs secured 45 on the faces of the asbestos 5 by wrapping asbestos cord 6 round the limbs.

Although the aggregation or mass of carbon constituting the pre-heater and vaporizer preferably takes the form of a sleeve it may be of other construction. 50 For instance, as shown in Figs. 6 and 7, it may be constructed of a flanged tube 7 of porcelain or other suitable insulating material provided with suitably spaced fins 7^I and of segments 1^I of carbon housed in the 55 spaces obtaining between said fins 7^I and secured in position and electrically connected to one another by means of two or more wires 8 engaging with grooves in the segments and the edges of the fins. 60 Alternatively, as shown in Figs. 8 and 9, the pre-heater and vaporizer may consist of a flanged tube 7 of porcelain or other insulating material, and of discs 1^{II} of carbon which are separated from one another by discs 7^{II} 65 of insulating material and are electrically connected to one another by means of long screws 8^I passing through the two sets of discs and engaging with the flange of the tube 7. Or, as shown in Figs. 10 and 11, the pre-heater and vaporizer may be constructed of 70 a flanged tube 7 of porcelain or other insulating material and of concentrically disposed sleeves 1^{III} of carbon, the latter being electrically connected to one another by means of screws 8^{II} passing through all of 75 the sleeves and engaging with the tube 7.

The pre-heater and vaporizer may be used with many constructions of carburetors without entailing any structural alterations 80 therein. A suitable construction of carburetor is illustrated by Fig. 12.

This carburetor comprises an annular chamber 9, a float 10 of corresponding shape, and a jet 11 arranged in the axis of the chamber 9 and connected by a tube or tubes 12 to said chamber, the inner periphery of which is shaped to form or has secured to it a fitting 13 of the shape necessary to form the choke-bore of the carburetor. The annular float chamber 9 is supplied with paraffin or other liquid fuel from a chamber 14 located at one side of the float chamber and communicating therewith by means of an orifice 15. The supply chamber 14 is formed at its bottom with a nipple 16, which is connected by means of a tube 17 to the tank supplying the liquid fuel to the carburetor and is provided at its upper end with a seating 18 for a needle valve 19. This needle valve 19, suitably guided in the supply chamber 14, is controlled by means of a rocking lever 20 operated by the float 10. The bottom wall of the float chamber 9 is preferably heated by the exhaust gases of the engine. This heating may be effected by means of an annular chamber 21 arranged immediately below the float chamber 9 and connected by a pipe 22 to the exhaust pipe of the engine, the bottom wall of the float chamber being preferably formed with annular depressions or pockets 9^I, so as to increase the heating effect of the exhaust gases on the liquid fuel contained in the float chamber, and the inner walls of the annular heating chamber 21 being provided with 105 ribs 21^I to cause heating of the air drawn into the carburetor. The tube 17 conveying liquid fuel to the carburetor is preferably coiled around the pipe 22 by which the exhaust gases are conveyed to the annular heating chamber 21. The quantity of liquid fuel issuing from the jet 11 of the carburetor is controlled by means of a valve consisting of a coned disc or button 23 adapted to operate with a corresponding seating 24 formed in the upper end of the jet 11. The valve 23 is removably mounted on a spindle 25 engaging with screw threads 26 formed in the lower part of the jet casting. 110

Having now described my invention what 120

125

130

I have invented and desire to secure by Letters Patent of the United States is:—

1. A pre-heater and vaporizer for application to the jet of the carburetor of an internal combustion engine consisting of an insulated aggregation of carbon.
2. A pre-heater and vaporizer for application to the jet of the carburetor of an internal combustion engine consisting of an insulated sleeve of somewhat porous carbon, substantially as described.
3. A pre-heater and vaporizer for application to the jet of the carburetor of an internal combustion engine comprising an insulated aggregation or mass of carbon and means for enabling said pre-heater to be connected to wires leading to a battery, said means consisting of strips of metal of approximately L-shape one of the limbs of each of which strips is formed at its outer end 20 with a hook and is bent so as to fit the pre-heater, while the other limb of each strip, provided at its outer end with slots, is bent at its junction with said first named limb upwards and at right angles to said limb, is 25 engaged with the hook at the end of said limb, and is then bent downwards on to the outer part of said hook, substantially as described.

In testimony whereof I have signed my 30 name to this specification.

LEON ALEXANDER DE BECKER.
